UNITED STATES PATENT OFFICE.

DELANEY ARKWRIGHT, JR., OF NEWTON FALLS, OHIO.

BURNER.

Application filed February 24, 1922. Serial No. 538,927.

To all whom it may concern:

Be it known that I, DELANEY ARKWRIGHT, Jr., a citizen of the United States, residing at Newton Falls, in the county of Trumbull and State of Ohio, have invented a new and useful Burner, of which the following is a specification.

This invention relates to furnace attachments, and aims to provide novel means for directing air and powdered fuel to the burner of a furnace in proper proportions to facilitate the burning thereof.

Another object of the invention is to provide means for adjusting the fuel supplying nozzles with respect to each other to insure the fuel being properly mixed with the air entering the furnace.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view of the attachment disclosing the same as connected with the fuel intake opening of a furnace.

Figure 2 is an end elevational view of the attachment.

Figure 3 is a sectional view through the attachment.

Referring to the drawing in detail, the reference character 5 designates a laterally extending pipe formed integral with the furnace casing, which pipe provides the fuel feeding opening to the furnace.

The attachment comprises a body portion 6 formed with a circumferential flange 7 adapted to abut the flange 8 formed on the pipe 5, where the flanges may be secured as by means of the bolts 9.

The outer end of the body portion 6 is formed with cut out portions 10 to permit air to pass into the body portion, suitable means being provided for controlling the passage of air through the openings 10. As shown, a pivoted member 11 is provided which pivoted member has portions overlying the openings 10 and cut off the air entering the body portion 6, should it be de-

sired to reduce the quantity of air passing 55 into the body portion 6.

Pipes 12 are formed integral with the body portion 6 and extend at angles with respect to the side walls of the body portion, the outer or free ends of the pipes 12 60 terminating at points in the same plane with the front end of the body portion 6. Adjustably supported within the pipes 12 are the pipes 13, which pipes are formed with flanges 14, by means of which the pipes may 65 be connected with a suitable blast of air for feeding powdered coal into the body portion 6.

Thus it will be seen that by moving the pipes 13 within the pipes 12, the inner ends 70 of the pipes 13 will be moved towards and away from each other to accomplish the adjusting result. It might also be stated that due to the positions of the pipes 13, the blast of powdered coal passing from one 75 pipe intersects the blast of powdered coal passing from the opposite pipe causing the powdered coal to be thoroughly mixed with the air passing through the openings 10.

A pipe 15 extends from the body portion 80 6 and provides means for securing the supply pipe 16 to the body portion, the supply pipe 16 providing means for directing a blast to the body portion or mixing chamber 6 for pre-heating the mixing chamber and 85 facilitating the starting of the burning operation.

Pipes 17 also communicate with the pipes 13 and supply a blast to the pipes 13 to pre-heat the pipes and aid in the burning of the 90 fuel.

In the use of the device, a blast is directed through pipe 16 and into the body portion or mixing chamber 6, where the same causes the mixing chamber 6 to become heated. 95

When the mixing chamber becomes heated to the proper degree, the blast through the pipe 16 is cut off and powdered coal is admitted to the pipes 13, the pipes 13 being however properly adjusted to cause the 100 proper mixing of the powdered coal and air.

Having thus described the invention, what is claimed as new is:—

In combination with a furnace, a body portion in communication with the furnace, 105 a fuel supply pipe in communication with the body portion, pipes extending at angles with respect to the body portion and having

their outer ends disposed in a plane beyond one end of the body portion, angularly disposed air delivering pipes positioned in the first mentioned pipes and adjustable longitudinally thereof, and having their delivering ends disposed towards each other, and terminating at points in spaced relation with the fuel supply pipe.

In testimony that I claim the foregoing as my own, I have hereto affixed my signature to in the presence of two witnesses;

DELANEY ARKWRIGHT, JR.
